Primary Examiner — Lauren D McVey(74) Attorney, Agent, or Firm — Tarter Krinsky & Drogin LLP(57) CLAIM

An ornamental design for an ink cartridge, as shown and described.

DESCRIPTION

FIG. 1 is a top perspective view of an ink cartridge;

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a top plan view thereof; and,

FIG. 7 is a bottom plan view thereof.

The portions of the article in broken lines are shown for illustrative purposes only and form no part of the claimed design.
